UNITED STATES PATENT OFFICE.

DAVID CARLIN, OF BELLEVUE, PENNSYLVANIA.

LEAD-PRESS.

No. 882,742.

Specification of Letters Patent. Patented March 24, 1908.

Application filed July 11, 1907. Serial No. 383,197.

To all whom it may concern:

Be it known that I, DAVID CARLIN, a citizen of the United States, residing at Bellevue, in the county of Allegheny and State of Pennsylvania, have invented certain new and useful Improvements in Lead-Presses; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to an improvement in lead presses, and it consists in the arrangement of such machines in pairs, side by side, each operating independent of the other and jointly, as desired, and the invention further consists in constructing and arranging the housing and head block from a single casting, thereby eliminating all loose parts and keeping the cylinders and other parts in perfect alinement, which is a very important feature, owing to the high pressure and strain upon the parts, and the invention further consists in utilizing the column at the front of the machine for removing and replacing the heavy parts of the apparatus, such as lead cylinders, plungers, &c., and the invention further consists in so arranging the lead cylinders to be operated alternatively; the one being permitted to cool while the other is in use, and the invention still further consists in the certain details of construction and combination of parts, as will be fully described hereinafter.

In the accompanying drawings;—Figure 1 is a front elevation of my improved lead press, a part of which is shown in section, the said press being constructed and arranged in accordance with my invention. Fig. 2 is a sectional plan view of the same, said section taken on the line X—X, of Fig. 1. Fig. 3 is a vertical section taken through one of the lead cylinders and mandrel, in which a removable and interchangeable bushing is arranged, by means of which various sizes of pipe and special work may be made. Fig. 4 is an enlarged sectional elevation of the sliding clutches arranged in connection with the front column of the press, said clutches used for elevating, lowering and manipulating various parts of the apparatus. Fig. 5 is an enlarged front elevation of the press, a part of which is in section, showing

the manner in which the hydraulic plungers or rams may be easily and quickly removed or replaced by the use of the clutches and power of the second cylinder of the press. 60

To put my invention into practice, I form from cast metal, such as steel, a heavy housing or frame, which I prefer to make in a single piece, said frame comprising a rear plate or back wall 1, with side webs 2, and outwardly projecting head piece 3 at the top and two hydraulic cylinders 4 and 5, at the base. These several parts of the frame may be made in sections, if desired.

Extending from the head piece 3, at the top, to an integral boss on the frame at the front of the cylinders 4—5, is a strong column 6, threaded at the top and bottom and fitted with nuts 7, the said column being used for the double purpose of tying and supporting the head block 3, to make the same rigid against the enormous strain and used for supporting sliding clutches 26 and 26', which together with the use of the hydraulic cylinders, act as a means for removing and replacing the heavy parts of the press, as will be fully described hereinafter. 70 75 80

Operating in the cylinders 4 and 5, are plungers or rams 9 and 9', said cylinders being copper lined and fitted with inlets 10 at the base for elevating said plungers and second inlets 11 at the top for lowering the same, together with the several valves and connections (not shown) common to this class of apparatus. These cylinders are arranged side by side in a vertical position and are fitted at the top with heads 13, through which the plungers project, and said plungers fitted with a plate or head piece 14, upon which the lead cylinders 17 and 17' and mandrel plate 15 are supported. These lead cylinders 17 and 17' are attached to the head piece 14, of the plungers 9 and 9' by bolts 16, passing through lugs formed with said cylinders and head pieces. Supported by the mandrel plates 15, and arranged within the lead cylinders 17—17', are centrally located, vertically-arranged mandrel bars 18, which are formed with enlarged tapering base and slender integral rods, which project a short distance above the open top of said cylinders, said base portion being fitted into a corresponding tapering socket formed in the center of the mandrel plate 15. This mandrel bar 18 is cylindrical in form and of a diameter equal to that of the inside of the pipe to be formed by the press. Located 90 95 100 105 110

over each lead cylinder 17 and 17', and in direct axial line, are mandrels 19-19', having a central bore, a flanged head, through which bolts 21 are passed to secure said mandrel in position to the head block, and each mandrel fitted at the base of said bore, with a die 20, the opening of which equals the external diameter of the pipe to be produced.

The operation of the double lead press, 10 above described, is as follows. The molten metal is poured into one of the lead cylinders 17 or 17', to form a charge, said metal being introduced through the medium of a spout (not shown) entered through an opening 35, 15 formed in the rear wall 1 of the frame, located immediately at the rear and above the top of said cylinder. The charge is permitted to cool to bring the same to the proper temperature for working. Pressure is now applied 20 to the ram 9, at the bottom through the inlet 10, and the work of forcing the charge is commenced. A charge is now placed in the second cylinder in the same manner as before described and the same permitted to cool 25 until the charge in the first cylinder is exhausted, or until such time as the proper temperature has been reached. When the first cylinder is exhausted the pressure is shut off from below and simultaneously 30 turned through the upper inlet 11, to bring the plunger 9 and its connected parts down to their normal position and pressure let into the cylinder 5, to force its plunger upward. The first cylinder is recharged and the operation 35 continued, thus working the two lead cylinders alternatively. With a variable speed pump the operation of lowering the lead cylinders to their normal position may be greatly expedited. The lead in the cylinders 17, 17', is forced through the dies 20 and passes out through openings 21, formed in the head piece, as the mandrels 19-19' enters the said cylinders, in a manner well known in the art. The advantages of this 40 double press are obvious. Heretofore single cylinder presses are used in all lead pipe making plants, the frames of such presses being built up of a number of parts which are difficult to keep in such perfect alignment to insure the lead cylinders, the mandrels and plungers or rams in a direct line, the one with the other. With this solid integral frame or housing such trouble cannot occur, and aside from this particular advantage the 45 press has double the capacity with practically the same operating expense in so far as actual labor is concerned, as it takes the same number of men to operate the single as the double press. In connection with this 50 style of lead press, the front column 6, with the hydraulic rams 9-9', are utilized to remove and replace the heavy parts when changes are made, which changes are of frequent occurrence in the making of different 55 sizes and weight of pipe and special work,

such as the covering of cables with lead. This I accomplish by arranging sliding clutches or carriers, the one 26 above the other 26', the one carrier being mounted directly upon the column 6 and the other 26 upon a flanged sleeve 30, with intermediate ball bearings 31, the several parts being held together by a collar 32, and set screw 33. Each of these carriers is provided with short radial arms to form an inclosed space 29, for the reception of suitably placed radial lugs 28 28' on the exterior and integral with the lead cylinders, and each of said lugs and said arms provided with registering openings in which pins 27-27', are placed to connect 60 said carriers with the lead cylinders. With these carriers, either the lead cylinders may be removed or replaced by simply disengaging the cylinder to be moved from its plunger (as at Fig. 1) connecting or coupling the top 65 carrier 26 thereto and coupling the bottom carrier 26' to the other cylinder 17'. When this has been accomplished, pressure is introduced at the bottom of the hydraulic cylinders 5, causing the plunger 9' to travel up- 70 ward, carrying both lead cylinders with it until the proper elevation above the plunger 9 is attained, at which time said lead cylinder to be removed may be swung outward, free of the press (as in dotted lines at Fig. 2) and 75 lowered to a buggy in waiting beneath, uncoupled by removing the pin 27 and swing the carrier free from the lug 28. The cylinder thus removed may be transferred to a warming oven or otherwise disposed of. It 80 is obvious that when the cylinders are thus coupled to the carriers, the parts may be either elevated or lowered by manipulating the plunger 9' by introducing the pressure either through the top 11, or bottom inlet 10. 85

At Fig. 5 of the drawings, I have shown, the manner in which one of the plungers may be removed by the use of the carriers, the second plunger and a swinging bracket loosely connected at the top of the column 6. 90 This swinging bracket 36, is held at the top of the column 6 by a collar 37, and is free to swing in the arc of a circle, and is fitted with a pulley or grooved wheel 38. To remove one of the plungers by the aid of this apparatus, a short section of rope 39 is used, the one end of which is attached to the lower carrier by means of a removable piece 42, held in position by means of the coupling pin 27' and the other end provided with a hook 40 whereby it may be attached to the head of said plunger 9' by means of a clip 41 fastened by short stud bolts, the threaded openings for which having been formed in said head for this purpose. 100

When the parts are together, as above described, having first removed the lead cylinder 17' and the cylinder head 13 and the plunger 9 being in an elevated position, pressure is introduced into the cylinder 4 through 105 110 115 120 125 130

the top inlet 11, to force said plunger 9 downward, which movement will lift the second plunger 9' free from its cylinder, and by swinging the bracket 36 outward, the same 5 may be lowered to a buggy or car placed at the front of the press. The plunger 9' to be removed is first elevated by the pressure beneath, to about the position shown in Fig. 5, of the drawings and the hook 40 engaged 10 with the clip 41. The carriers and column may also be used when special work is called for, for instance, when alloyed metals are used, the melting of the same may be done at a convenient point in front of the press, 15 poured into the lead cylinders and swung into position on the press. By this means two cylinders (one on each press) may be used alternatively, if desirable, in order to allow sufficient time for charging and cooling.

To remove the mandrel bars 18 from their sockets in the bottom plates 15, the lead cylinders are coupled to the carriers as at Fig. 1, of the drawings, and by the use of a small 25 upwardly projecting tool 42, placed on the head of the plunger 9, and a flat piece (not shown) on top of the lead cylinder to prevent its mandrel from entering therein. Pressure is now applied in the bottom of the cylinder 30 4 to move the plunger 9 upward, and as the lead cylinder has been rendered immovable, the pressure is exerted upon the tapering base of the mandrel bar, thereby forcing the same from its socket.

Various slight modifications and changes 35 may be made in the details of construction without departing from the spirit of the invention. Therefore I do not wish to confine myself to the exact construction, shown and 40 described, but wish to claim all such modified forms as would come properly within the general scope of the invention.

Having thus described my invention, what I claim, and desire to secure by Letters Patent, is;

1. A lead press comprising a frame formed from a single piece of cast metal, said frame comprising a back wall, a head block and two hydraulic cylinders, the back wall being 50 provided with charging openings, a column connecting the cylinders with the head block, plungers operating in said cylinders, the one independent of the other, means for introducing pressure to operate said plungers, 55 lead cylinders attached to each of said plungers, mandrel plates between the lead cylinders and plungers and provided with sockets, mandrels located above said lead cylinders and in line therewith, dies located in said 60 mandrels, and mandrel bars located in said

lead cylinders adapted to pass through said dies and having tapered heads on their lower ends engaging said sockets, as and for the purpose described.

2. A frame for a lead press comprising an 65 integrally formed back wall, side walls, head block, and hydraulic cylinders, and a front column for connecting the hydraulic cylinders with the head block.

3. In a hydraulic lead press as described, a 70 supporting frame having a head block, a pair of hydraulic cylinders carried by said frame, a front column tying the cylinders to the head block, plungers operating in said cylinders, lead cylinders connected to each of said 75 plungers, mandrels carried by the head block in line with said lead cylinders, dies located in said mandrels, and mandrel bars located in said lead cylinders adapted to pass through said dies.

4. In a double lead press, a supporting frame embodying a back wall provided with charging openings, side walls, a head block, and a pair of hydraulic cylinders, the back wall, side walls, head block, and cylinders 85 being in one piece, a front column connecting the cylinders with the head block, plungers operating in said cylinders, lead cylinders carried by said plungers, mandrels carried by the head block in line with the lead 90 cylinders, dies in said mandrels, mandrel bars in said lead cylinders adapted to pass through said dies, slideable carriers on said front column, means for connecting said slideable carriers to the lead cylinders, a swinging 95 bracket on the front column and means for connecting the swinging bracket with one of the plungers and with one of the carriers on the column, as and for the purpose described.

5. In a double lead press, the combination with a supporting frame having a head block, and a pair of hydraulic cylinders carried thereby, of plungers operating in said cylinders, a front column connecting said hydraulic cylinders with the head block, lead cylinders carried by said plungers, slideable carriers on said front column, means for connecting said slideable carriers with the lead cylinders, a swinging bracket on said column, and means for connecting said swinging bracket with one of the plungers and with one of said slideable carriers.

In testimony whereof, I affix my signature, in presence of two witnesses.

DAVID CARLIN.
